APPAREL HOLDER FOR COAT HANGERS

Dudley C. Kleist, Portland, Oreg.

Application August 27, 1949, Serial No. 112,667

5 Claims. (Cl. 223—88)

1

This invention relates to a device to be applied to a wire coat hanger and the like for supporting articles of wearing apparel.

Wire coat hangers are extensively used by cleaning and pressing establishments for delivering various types of garments. Such hangers have shoulder supports for articles of clothing such as coats, vests, jackets and dresses, and a horizontal bar for supporting trousers and skirts. This type of hanger, however, ordinarily includes no satisfactory provision for holding smaller articles such as neckties, dress belts and the like. Articles of this kind are often draped loosely over the bar of the hanger from whence they may easily slip off and become lost. Small articles are sometimes pinned together beneath the bar but this cannot be accomplished in a satisfactory manner if also there is a large garment on the bar. Even though ties, belts and the like may be pinned on the hanger bar, they still have sliding freedom to crowd to one end of the hanger and become wrinkled.

The general object of the present invention is therefore to provide improved apparel holding means for wire coat hangers to hold small articles such as neckties and dress belts in a neat and orderly arrangement so that they will not become lost or wrinkled regardless of the presence or absence of other garments on the hanger.

A further object is to provide a supporting member of stiff sheet material having a plurality of article holding openings to hold small articles on a coat hanger in spaced relation, and having means for preventing such articles from slipping out of their openings. A further object is to provide a tubular garment support for coat hangers having an improved form of rolled edge to facilitate insertion of the coat hanger for installing the support on the horizontal bar of the coat hanger.

The invention will be more readily understood from the following description having reference to a preferred embodiment illustrated in the accompanying drawings.

In the drawings:

Figure 1 is a view of the present device applied to a wire coat hanger and carrying a necktie and belt in two of its article supporting openings;

Figure 2 is a cross-sectional view taken on the line 2—2 of Figure 1;

Figure 3 is a fragmentary perspective view showing the function of the rounded corners in the tubular portion of the article holding member; and

Figure 4 shows a modification having a different form of article engaging means.

2

The numeral 10 refers generally to a common type of wire coat hanger having a hook 11, laterally extending sloping shoulder bars 12 to carry coats, jackets, vests and dresses, and a horizontal bar 13 to carry trousers, skirts and other articles of apparel. It is the usual practice to hang neckties and dress belts over the horizontal bar 13. If there is some larger article of apparel already on the bar 13, such as a pair of trousers, the smaller articles are ordinarily draped loosely thereover, but if there is nothing else on the bar the smaller articles will then slide freely to one end or the other and become wrinkled in the angle or corner 14.

15 The invention comprises a combined guard or shield and article holding member 15 formed from a single sheet of cardboard or the like. The upper portion of this sheet is rolled from its edge 16 to form a stiff tube 17 for supporting the remainder of the sheet in a vertical hanging position from the bar 13 of the hanger. The member 15 is assembled on the hanger by passing the bar 13 between overlapped portions of the sheet which form a double thickness wall on one side of the tube 17 so that the bar 13 is disposed within the tube as shown. To facilitate assembly 20 the upper corners of the sheet are rounded as at 20 to form a spiral approach to the top edge 16 within the tubular roll. The parallel vertical side edges 21 of the sheet extend most of the way around the ends of the tube and over the top of the bar 13 and the tube is of sufficient length between the edges 21 to crowd these edges substantially into the corners 14 so that the holder 15 cannot move longitudinally on the bar.

25 Figure 3 illustrates how the rounded corner 20 forms a spiral guide to lead the coat hanger wire easily into the center of the tube past the edge 16, permitting the device to be assembled more rapidly than if the ends of the tube were 30 square cut all around the circumference. The preferred assembly technique is to grasp the member 15 in the left hand and the hanger 10 in the right hand and press the outer part of the curved wire at one corner 14 against the rounded corner 20 with the bar 13 slightly inclined to the axis of the tube 17 as shown in full lines. Then, the corner 14 of the hanger may be caused to follow around the corner 20 until the bar 13 passes behind the edge 16 whereupon the corner 14 then follows the edge 16 with the bar 13 inside the tube as shown in broken lines. Little dexterity is required to insert a hanger in one rapid continuous movement of the right hand. The rounded corner 20 also forms a guide 35 for the inside surface of corner 14 so that a

hanger may be removed from the tube in one simple longitudinal movement without damaging the tube. By thus facilitating the assembly there is less natural inclination for the operator partially to unroll the tube 17, which might impair the function of the holder 15.

The vertical hanging portion of the sheet 15 in Figure 1 is provided with a series of horizontal cuts or scores 25 and vertical cuts or scores 26 which form a series of spring tabs 27 and openings 28 having article supporting lower edges 30. A number of small articles such as the necktie 35 and belt 36 may be thrust through the openings 28 to hang in spaced relation distributed along the length of the bar 13, each article being engaged by the lower edge of a tab 27 to prevent it from slipping out. Thus the individual openings 28 for each article keep the articles separated and unwrinkled, and the parallel edges 21 of the sheet by being in substantial engagement with the corners 14 of the hanger prevent any longitudinal movement of the whole assembly on the bar 13. When a necktie is doubled and the loop pushed through an opening as shown, the lower edge of the tab 27 acts as a pawl to bind the thick part of the loop against slipping back while at the same time the weight of the long ends prevents the loop from slipping through further in the direction in which it was inserted. Also, the length of the opening 28 is preferably less than the greatest width of a necktie to prevent the large end from pulling through.

The present device does not impair the use of the hanger for larger articles of apparel but rather facilitates such use as it provides the large stiff tube 17 for supporting trousers and the like which would otherwise have to be folded sharply over the thin bar 13. Any small articles suspended in the openings 28 are held flat and protected beneath the larger and heavier garments, which is of advantage in handling and delivering the garments in the business of a cleaning and pressing establishment.

Advertising matter or other printing may be applied to the flat portion of the sheet 15 right across the article supporting openings 28 inasmuch as the tabs 27 normally close these openings and preserve the continuity of the sheet for display purposes.

In the modification shown in Figure 4, the horizontal cuts 41 and 42 and vertical cuts 43 form pairs of tabs hinging as at 44 on opposite sides of apparel openings. When a loop of the necktie 35 is inserted, the tabs 45 are spread apart somewhat at their ends, and the lower edges of the tabs engage the necktie by spring action to exert sufficient binding action to prevent slippage. Here again it is preferable to double the tie and push the loop only a short distance through the tabs so that the greater weight will hang on the side of the sheet 15 opposite the pushed out tabs.

What is claimed is:

1. A combination guard or shield and article holder for use with a wire coat hanger having a horizontal bar, comprising a sheet of stiff material having a rolled portion to encircle said bar and support the remainder of the sheet in a vertical hanging position, rounded on said rolled portion forming a spiral guide edge to facilitate insertion of said hanger bar, said sheet being provided with a series of intersecting horizontal and vertical cuts to form openings having lower edges for supporting articles inserted

through said openings, and tabs coextensive with said openings and having lower edges for engaging articles inserted through said openings to prevent the articles being displaced therefrom.

5 2. An article holder for use with a wire coat hanger having a horizontal bar, comprising a sheet of stiff material having a rolled upper portion to encircle said bar and support the remainder of the sheet in a vertical hanging position, said sheet having vertical and horizontal cuts to form a series of openings having lower edges for supporting articles inserted through said openings, and tabs coextensive with said openings and having lower edges for engaging articles inserted through said openings to prevent said articles being displaced therefrom, said tabs presenting a substantially continuous surface across said sheet for printed matter.

3. A holder for small articles of apparel on a wire coat hanger having a horizontal bar connected at the lower corners of the hanger with sloping shoulder bars, comprising a sheet of stiff material having a rolled upper end to encircle said bar and support a portion of the sheet in a vertical hanging position, said sheet having parallel side edges forming ends on said roll to engage said corners of the hanger and prevent longitudinal movement of the roll on said bar, rounded corners on said sheet within said roll to guide the hanger wire into the roll in assembling the holder on the hanger said sheet having, horizontal and vertical cuts in the hanging portion thereof forming a series of article supporting openings having lower edges for supporting articles inserted through said openings, and tabs coextensive with said openings and having lower edges for engaging articles inserted through said openings to prevent the articles being displaced therefrom.

40 4. An article support for carrying small articles of apparel beneath a folded garment on a horizontal coat hanger bar, comprising a member having a tubular portion to encircle said bar and support a garment on the bar, and a vertical free hanging sheet on said tubular portion having a series of intersecting horizontal and vertical cuts forming openings having lower edges for supporting articles inserted through said openings, and tabs coextensive with said openings and having lower edges for engaging articles inserted through said openings to prevent the articles being displaced therefrom.

45 5. An article support for carrying small articles of apparel on a horizontal coat hanger bar, comprising a member having a tubular portion to encircle said bar and a vertical sheet adapted to hang from said tubular portion, said sheet having a series of horizontal and vertical cuts therein forming openings having article supporting edges, and flexible tabs coextensive with said openings and having lower edges formed by said horizontal cuts, said lower edges of the tabs being coextensive with the length of said cuts to engage articles on said supporting edges over substantially the entire length of each edge.
